INVENTOR

BY *Victor J. Evans*

ATTORNEY

UNITED STATES PATENT OFFICE.

EDWARD E. JONES, OF ROCKFORD, ILLINOIS.

TELEPHONE HOLDER.

Application filed July 28, 1926. Serial No. 125,524.

This invention relates to a support for a telephone, the general object of the invention being to provide means for adjusting the distance the telephone is from the floor so that it can be readily moved to the most convenient position by the person using it.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a longitudinal sectional view of the supporting means for the telephone.

Figure 2 is a section on line 2—2 of Figure 1.

Figure 3 is a perspective view of the supporting bracket for the telephone.

In these views, 1 indicates an upright pipe which is held to the floor and ceiling of a booth or other support by the socket members 2 and 3 indicates a small pipe or tube which is fastened to a portion of the pipe 1 by the clamps 4. Each clamp is shaped to partly embrace both the tube 3 and the pipe 1, with its split ends fastened together by the bolt 5. A slot 6 is formed in the tube 3. A small weight 7, of circular shape in cross section, is slidably mounted in the tube 3 and a large weight 8 is slidably arranged in the pipe 1. These weights are connected together by the cable 9 which passes over a pulley 10 placed in an opening 11 in the pipe 1. A bracket 12, to which the telephone A is fastened by screws, bolts or the like,

is attached to the weight 7 by the straps 13 which are placed in grooves in the weight 7 and are bolted or otherwise fastened to the bracket. 45

The weight 8 will counterbalance the weight 7, the telephone and its bracket and thus hold the telephone in adjusted position, but will permit the said telephone to be either raised or lowered by a slight pressure 50 on the same. Thus a person using the telephone can quickly and easily adjust it to a position where the mouthpiece will be level with his mouth so that it is not necessary for the person to stoop in order to reach 55 the mouthpiece or to stand on his tiptoes or upon an object, as he would if the telephone were too high.

It is thought from the foregoing description that the advantages and novel features 60 of my invention will be readily apparent.

I desire it to be understood that I may make changes in the construction and in the combination and arrangement of the several parts, provided that such changes 65 fall within the scope of the appended claim.

What I claim is:—

An adjustable support for a telephone, comprising a tubular upright, a weight movably arranged therein, a slotted tube, clamps 70 for connecting the tube to the upright, a weight slidably arranged in the tube, a cable connecting the weights together, a guiding pulley on the upright for the cable, a supporting bracket for the telephone and 75 clamps for connecting the bracket to the weight in the tube, said weight having grooves therein for receiving portions of the clamps.

In testimony whereof I affix my signature. 80

EDWARD E. JONES.
